UNITED STATES PATENT OFFICE.

ALBERT SHUTT, OF TOPEKA, KANSAS.

DESIGN FOR A BODY FOR STRINGED MUSICAL INSTRUMENTS.

40,564.

Specification for Design.

Patented Mar. 8, 1910.

Application filed December 6, 1909. Serial No. 531,745. Term of patent 7 years.

To all whom it may concern:

Be it known that I, ALBERT SHUTT, a citizen of the United States, residing at Topeka, in the county of Shawnee and State of Kansas, have invented a new, original, and ornamental Design for Bodies for Stringed Musical Instruments, of which the following is a specification, reference being had to the accompanying drawing, forming part thereof.

Figure 1 shows the design of the body of

a stringed musical instrument in front elevation, the upper portion of the finger board being removed; Fig 2 is an edge view thereof.

I claim:

The ornamental design for a body for stringed musical instruments, as shown.

ALBERT SHUTT.
